US00D710018S

(12) **United States Design Patent**
Forbes et al.

(10) **Patent No.:** **US D710,018 S**
(45) **Date of Patent:** **** Jul. 29, 2014**

(54) **KNEE BRACE**

4,084,584 A 4/1978 Detty
4,099,269 A 7/1978 Porner
4,116,236 A 9/1978 Albert

(71) Applicant: **Ossur hf**, Reykjavik (IS)

(Continued)

(72) Inventors: **James Forbes**, Costa Mesa, CA (US);
Brice Robertson, Sunnyvale, CA (US)

FOREIGN PATENT DOCUMENTS

(73) Assignee: **Ossur Hf**, Reykjavik (IS)

CA 2 038 948 A1 2/1991
DE 30 28 381 A1 2/1982

(**) Term: **14 Years**

FIG. 1 is a first side elevational view of a knee brace, showing our design.

FIG. 2 is a front elevational view of the knee brace thereof; FIG. 3 is a rear elevational view of the knee brace thereof; FIG. 4 is second side elevational view of the knee brace thereof;

FIG. 5 is a top view of the knee brace thereof; and,

FIG. 6 is a bottom view of the knee brace thereof.

The broken lines are included for the purpose of illustrating environmental structure and form no part of the claimed design.
